M. K. ARMSTRONG

PLASTER BOARD

Filed Dec. 12, 1921

Inventor
Morgan K. Armstrong
by Clarence C. McElroy Atty.

UNITED STATES PATENT OFFICE.

MORGAN K. ARMSTRONG, OF WINNETKA, ILLINOIS.

PLASTER BOARD.

Application filed December 12, 1921. Serial No. 521,576.

This invention relates to improvements in plaster board and consists of the matters hereinafter described and more particularly pointed out in the appended claims.

5 The invention is addressed specifically to a plaster board of the kind comprising top and bottom covering sheets of paper or other fibrous material and an interposed body of plaster, the main ingredient of 10 which is gypsum, to which body the covering sheets are adhered by reason of the adhesive character of the plaster comprising the body.

Plaster board of the kind has been made 15 with the plaster body exposed at the edges, and has also been made with the edges of the plaster body bound or protected by means of extensions on one of the covering sheets, which are turned about said edges 20 and over on top of the opposite side of the board,—the extensions being sealed either under or on top of the edges of the other sheet by means of the plaster material of the body. The object of thus binding the 25 edges of the sheet is to provide smooth, square edges for the board and also to reinforce the board at the edges and prevent it from breaking when handled or by the action of nails when nailing it in place.

30 The object of my invention is to provide a plaster board of the kind with substantially straight, true, square edges, without the necessity of binding the edge by extensions of one of the covering sheets, and at 35 the same time to provide said board with edges which may be nailed in position without breaking. The advantages of the invention will appear as I proceed with my specification.

40 In the drawings:—

Figure 1 is a perspective view of a width of board which may be cut into two lengths of board of the kind involving my invention.

45 Figure 2 is a view showing a transverse section through a board embodying the invention.

50 Figures 3 and 4 are detail, sectional views showing modified forms of the edge of the board, to be more particularly referred to later.

55 Referring now to the drawings:—particularly to Figure 2—10 indicates the top sheet of a board embodying my invention, and 11 indicates the bottom sheet. 12 indi-

cates the interposed body of plaster material which is of a familiar kind, and is made up largely of gypsum. Such a plaster board is well known to those familiar with the art. 13, 13 indicate strips or bands of a nailing mixture interposed between the top and bottom sheets of the plaster board at the edges of the board. This nailing mixture may be of any suitable composition comprising ingredients which will harden 60 and which will be of an adhesive character sufficient to become adhered to the overlying parts of the covering sheet of the board, and which will permit a nail to pass through it without breaking or disintegrating. Such 65 a mixture may be made of tar, sawdust or other fibrous material and clay, which are preferably mixed hot.

In the manufacture of the board, covering sheets 10, 11 of the width of the board 70 are used and the strips or bands of nailing mixture 13 are laid on the bottom sheet 11 at the edges of the sheet and the plaster body 12 is spread upon the bottom sheet in the space between said bands 13, both the 75 nailing mixture and the plaster body being applied when in a plastic condition. The top covering sheet is then applied and adhered by pressure to the intermediate body of plaster 12 and to the bands 13. In the 80 application of the pressure to the top sheet 10 the material of the plastic body 12 and the material of the nailing mixture bands 13 is forced into intimate engagement at the 85 proximate edges so that said edges will adhere together, thus providing when the 90 board is finished, a substantially integral body extending between the edges of the board. The outer edges 14, 14 of the nailing mixture bands may be made true and 95 square and flush with the edges of the covering sheets so that when the board is completed, its edges are smooth and true.

The board may either be made in the beginning of the desired width, or it may be 100 made of double width as shown in Fig. 1, according to my Patent 1,578,250, March 30, 1926. In said figure the top sheet 10^a and the bottom sheet 11^a are double the width of the intended board. In the manufacture of the 105 double width board, the nailing mixture bands 13^a, are provided at the outer edges of the main board and a wider nailing mixture band 13^b is provided in the middle of the board. Then after the double width board 110

is completed as before, it may be sawed along the middle line 15, thus providing two boards.

As shown in the drawings, in Figures 1 and 2, one of the sheets,—in this case the top sheet—is made to incline downwardly towards the edge of the board so as to provide a slight bevel 16 at the edge of the board. When the board is made in 10 a double width as shown in Fig. 1, the top sheet at the middle is beveled in both directions as indicated at 17, 17 towards the middle line 15, so that when sawed or cut through the middle, the edges along the line 15 will be similar to the other edges of the board.

Again the board may be formed without the aforesaid bevel, and with the edges made of the same thickness throughout, as illustrated at 18 in Figure 3. And the face of the edge may be flat as shown at 18^x or it may be made concave as indicated at 19^x in Figure 4, thus providing a space between two adjoining boards for a key. When the 25 board is made without the bevel, as in Figures 3 and 4, both faces of the board are identical, so that if one face is damaged it may be faced inwardly and the other may be faced outwardly.

30 I claim as my invention:—

1. A plaster board comprising a plaster body which is narrower than the board to be made, strips of substantial width of a nailing mixture of different composition from 35 that of the plaster body adhered to the lateral edges of said plaster body, and completing the designed width of said board,

top and bottom covering sheets of paper adhered to said plaster body and projected beyond the same to include within their 40 limits said strips, and said strips filling the entire depth of the spaces between the overlapping margins of said covering sheets and being adhered thereto.

2. A plaster board comprising a main 45 plaster body and nailing mixture strips adhered to the edges of said plaster body and forming the edges of the board, and top and bottom covering sheets of paper adhered to said plaster body and to the said 50 nailing strips, the top covering sheet adjacent the edges of the board being inclined downwardly toward said edges.

3. A plaster board comprising a plaster body formed of a core margined by edge 55 stratas of previously prepared composition having different characteristics than said core.

4. A plaster board comprising a plaster of Paris product body having its edges 60 formed of strips of previously prepared hardened reinforcing substance of different composition than the center.

5. A plaster board comprising a plaster of Paris product body having its exposed edges 65 formed of strips of previously prepared hardened reinforcing and waterproofing substance of different composition than the center, said body being disposed between fibrous covering sheets.

In testimony that I claim the foregoing as my invention, I affix my signature, this 8th day of July, A. D. 1921.

MORGAN K. ARMSTRONG.
